CLAIM

We claim the ornamental design for a building automation device, as shown and described.

DESCRIPTION

FIG. 1 is a top, front, left perspective view of a building automation device according to the claimed design;

FIG. 2 is a bottom, front, right perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the drawing views depict portions of the building automation device that forms no part of the claimed design.

Building automation devices include, but are not limited to, thermostats, sensors, lighting controls, building controls, and heating, ventilation, air-conditioning, and refrigeration equipment controls.
